INNER-SOLE

Robert M. Lehner, Lynn, Mass.

Application November 29, 1935, Serial No. 52,078

5 Claims. (Cl. 36—43)

The present invention relates to a method of preparing a paperboard or the like for use as a strip out of which an inner-sole for a shoe may be cut and also to the construction of the inner-sole itself.

In the prior art inner-soles have been fashioned from leather or paper and from other such similar materials. The inner-soles fashioned from paper have either been made throughout of the same material or they have been made of different kinds of materials and fastened together in some known fashion. In one type of inner-sole there is used a flexible center portion at the edges of which are glued stiff end portions of substantially the same thickness. These end portions and the center portions may be spliced together and adhered to each other by cement, glue or some similar material. Such a process is somewhat expensive, since the center portion must not only be cut on a bevel for proper splicing but the edge portions must be similarly cut and held together in place while cementing.

The present invention provides a strip or sheet out of which an inner-sole may be fashioned without the necessity of the procedure described above and yet the sole may have a flexible center portion and stiff edge portion which materially aid in the lasting of the shoe and the formation of a proper piece for the toe and heel support.

In the present invention the inner-sole is made out of the same piece of material but the strip or sheet is put through a proper process which makes the central portion flexible and the edge portion rigid. In the present invention the central portion may be made flexible and if desired an additional facing strip may be placed on the end portions extending higher than the surface of the central portion. In this case the bottom part of the inner-sole is composed uniformly of the same material but made more flexible in the center part than near the ends on the other side of which the hard flat strip or sheet may be placed. To this extent the inner-sole may also comprise a composite sheet of different materials. In the present case the applicant prefers to use a paper sheet that is commonly known as cylinder board although other types of pressed paper as press board or fiber board may under suitable conditions be used. In the present invention the sheet or strip out of which the inner-sole is made is finished in such a way that both end elements are stiff or hard so that in the cutting out of the inner-sole no material will be wasted, that is to say, the sole will face one way

and then the other way so that the maximum material possible will be used.

The present invention will be more fully described in connection with the drawing, in which:

Figure 1 shows in fragmentary section, a view of the strip out of which the inner-sole is formed.

Figure 2 shows a fragmentary plan view of a different strip from that shown in Figure 1 out of which the inner-sole may be formed.

Figure 3 shows a section taken on the line 3—3 of Figure 2.

Figure 4 shows an inner-sole as cut out of the strip of Figures 2 and 3.

Figure 5 shows a section taken on the line 5—5 of Figure 4.

Figure 6 shows a modified section in the same position as taken for Figure 5, and,

Figure 7 shows diagrammatically the machine for making the center portion flexible.

As indicated in Figures 2 and 3 the strip out of which the inner-sole may be cut is composed of a central flexible portion and stiffened end portions 2 and 3, or as indicated in Figure 1, the central portion 4 may be a flexible strip of the same material as the end portions 5 and 6. The end portions 5 and 6 however may be faced with a stiff piece of paper board as indicated by 7 and 8. These ends 7 and 8 may extend substantially from the base surface or they may be pressed downward to be practically level with the surface of the inner portion.

In Figure 4 there is indicated a different inner-sole which is fashioned out of the strips shown in Figures 2 and 3. In this case the end pieces 9 and 10 comprising the toe and heel respectively are the hardened portions, the central portion 11 being flexible. The whole inner-sole in Figure 4 is made out of a single continuous piece of material and the ends hardened by dipping them in a proper hardening bath, such for instance as shellac compound or a preparation of similar nature. The central portion is made flexible entirely by a mechanical process which is indicated in Figure 7. In this case there is provided a group of circular cutters 12, 12, 12, etc., which may be mounted on a single shaft 13 and driven through the pulley 14 from a proper power source. The cutters 12 provide substantial transverse cuts in the central portion of the strip as indicated in the drawing. Between the circular cutters are longitudinal cutters 15, 15, 15, which advance the strip 16 indicated in Figure 7 through the machine and at the same time provide the longitudinal markings or cuts as indicated more clearly.

ly in Figures 2 and 4. The strip as indicated in Figure 7 is laid on a piece 17 and is automatically fed by means of the longitudinal cutters 15 through the machine. It is preferable to have 5 one surface of the strip completed at a time. When one surface has been completed it is turned over and the opposite surface is finished. As indicated in the figures in the drawing the transverse cuts effected by the cutters 12, 12, 10 etc., are more or less surface cuts and do not extend for more than perhaps from one fifth to one tenth of the way through the inner-sole. In fact in an inner-sole of approximately $\frac{1}{8}$ th of an inch in thickness, the cut need only be 15 from .005 to .008 of an inch deep. The longitudinal cuts may be even less than the transverse cuts and in fact for the same thickness of inner-sole may be only .002 or .003 of an inch deep. The transverse cuts and also the 20 longitudinal cuts are preferably spaced apart about $\frac{3}{2}$ nds of an inch, and may as indicated in the drawing form substantially a square between. In this manner, the inner-sole when cut on both faces is made very flexible longitudinally 25 or the length of the strip and sufficiently flexible across the strip for effective use in a shoe. This is also an advantage over the soles of the prior art in that it is more flexible lengthwise than cross-wise and will therefore bend with the bending 30 of the shoe in the direction that the greatest flexibility is demanded but will otherwise preserve its shape and tend therefore to maintain the shape of the shoe. The cuts on both sides may be substantially aligned with one another, 35 but I prefer for greater flexibility to have them at least somewhat off alignment so that a uniform flexibility will be provided and no substantial weakening of the sole will be present as might occur where the cuts on opposite sides align with 40 one another and pierce a substantial part of the material. The process of making the inner portion flexible may take place after the inner-sole has been cut out, but is preferably accomplished with the material in strip form as it is possible to 45 run successive strips through the machine shown in Figure 7 by rapidly lining up each end edge with the next piece to follow through the machine.

As indicated in Figure 6 the heel portion 18 50 may be made higher than the central portion of the inner-sole, and this may be of different material such as fiber or press board from the lower piece 19 which is made flexible in the process described.

55 The inner-sole described above may be used in most any type of shoe and furnishes in particular a firm toe and heel portion thus helping in the fashioning on the last of these parts of the shoe. At the same time the central portion 60 of the inner-sole is flexible enough, particularly lengthwise of the shoe to allow the wearer perfect ease in walking. As has been remarked above, the flexibility of the inner-sole is greater

lengthwise than cross-wise of the shoe and this also tends to allow the shoe to keep its proper form.

It will be appreciated of course that within the description given above, the inner-sole or the 5 strip out of which the inner-sole is formed may be varied to some extent without substantially departing from the spirit of the invention herein described.

Having now described my invention, I claim: 10

1. An inner-sole made of a single piece of paper material, said material being stiffened by treatment at its heel and toe extremities and forming thereby stiff heel and toe portions and unstiffened center portions of the original paper 15 material providing a flexible center section therebetween, said flexible section having the surface thereof cut lengthwise and crosswise by parallel cuts spaced closely together and extending only for a slight depth into the material whereby said 20 center section is more flexible than the original paper and said extremities more rigid.

2. An inner-sole of the type described made of a single piece of paper material having stiffened toe and heel portions formed by treatment 25 of said toe and heel portions only and a flexible untreated center portion extending therebetween, said flexible center portion having longitudinal and transverse cuts spaced approximately $\frac{3}{2}$ nd of an inch apart and having a depth of from 30 .002" to .008" deep, whereby said center portion is made more flexible than the original paper and said extremities more rigid.

3. An inner-sole of the type described made of a single piece of paper material having a stiffened heel portion formed by treatment of said heel 35 portion and a flexible untreated middle portion extending from the heel portion to the toe portion, said flexible center portion having longitudinal and transverse cuts spaced substantially the 40 same distance apart and extending only through the surface of the material, whereby said center portion is made more flexible than the original paper and the heel portion more rigid.

4. An inner-sole of the type described made of 45 a single piece of paper material having a stiffened heel portion formed by treatment of said heel portion and a flexible untreated middle portion extending from the heel portion to the toe portion, said flexible portion having longitudinal and 50 transverse cuts approximately $\frac{3}{2}$ nd of an inch apart and extending from .002" to .008" into the material, whereby said center portion is made more flexible than the original paper and the heel portion more rigid.

5. An inner-sole of the type described made of a single piece of paper material having a stiffened heel portion and a flexible center portion extending from the heel portion to the toe portion, said flexible portion having longitudinal and trans- 60 verse cuts spaced about $\frac{1}{8}$ " apart, said transverse cuts being deeper than said longitudinal cuts.

ROBERT M. LEHNER.
